COIN PACKAGING DEVICE

Earl C. Carruthers, Providence, R. I.

Application October 10, 1947, Serial No. 779,175

3 Claims. (Cl. 133—1)

1

My invention relates to improvements in coin packaging devices of the type adapted to count and package a plurality of different types of coins. My invention is particularly adapted for use in counting a pile of coins of small denomination and wrapping them up in a standard bank package such as a package of 50 for pennies, a package of 40 for nickels, a package of 100 for dimes, a package of 20 for quarters, a package of 20 for half dollars. The specific embodiment shown is adapted to selectively count and package 50 pennies or 40 nickels.

While I am aware that others have provided various types of devices for this purpose, in general these have been cumbersome and bulky and have needed some type of operating device which protrudes therefrom and takes up space and often gets out of adjustment.

Objects of my invention, therefore, are to provide a single, simple, preferably transparent counter of a tubular shape which will positively count the right number of coins at all times without any external manipulating mechanism. To this end, I provide measured, predetermined distances for stacks of a definite number of coins, so that coins of the same sizes and value will positively have the same number in each stack at all times, in other words, a counter which changes automatically depending on the size of the coin counted so that it will positively count the same number of coins each time.

A further object of my invention is to provide a device which will also on inversion thereof slide the stack of coins into a tubular folded wrapper so as to complete the wrapping. After the stack of coins have been inserted therein, it is merely necessary to fold in the ends of said wrapper.

A further object of my invention is to provide a device of this description in which it is easy to insert coins and easy to remove them therefrom due to the fact that I preferably employ a conical pouring funnel at the upper end thereof.

A further object of my invention relates to the provision of a transverse slot at the upper limit of the selected stacks of coins whether they be of one value or the other, so that any excess coins may be slid off the top of the stack on tipping of the device so as to insure that the correct number only will be packaged.

A further object of my invention is to provide a device in which the coins are observable at all times and to this end I preferably provide my device of a transparent material such as a transparent synthetic resin, whether it be of the ace-

2

tate or methylacrylate type or otherwise and additionally provide it with a vertical slot so that the compactness of the stacking of the coins can be observed at all times through said slot.

5 A main object of my invention, however, which positively insures the exact number of different sized coins required to make a stack is that I provide a base of one diameter for a stack of coins of one denomination extending up from its base to said transverse slot and a base of a different diameter for a stack of coins of the other denomination also reaching up from its different base to said transverse slot.

A further object of my invention is to provide 15 a counter which may be readily used to count small change such as pennies and nickels now collected in large amounts in states having sales taxes and which provides a simple, fool-proof device for so counting said coins.

20 These and such other objects of my invention as may hereinafter appear will be best understood from a description of an embodiment thereof such as is shown in the accompanying drawings.

25 In the drawings:

Fig. 1 is a perspective view of a coin packaging device constructed in accordance with my invention.

Fig. 2 is a plan view thereof.

30 Fig. 3 is a front elevation showing how a stack of coins is inserted within my improved counter.

Fig. 4 is a side elevation showing how any excess coins which may have been inserted in the stack may be readily removed therefrom before 35 the stack of coins is wrapped.

Fig. 5 is a front elevation illustrating a folded paper wrapper inserted within the upper end of my improved device between the side wall of the device and the peripheries of the stacked coins.

40 Fig. 6 is a front elevation showing how on the inversion of the coins and counter, the stack of coins may slide from the counter into the wrapper.

Fig. 7 is a perspective view of the wrapped 45 coins after the ends thereof have been turned.

In the drawings, wherein like characters of reference generally indicate like parts throughout, 10 generally indicates a coin packaging device capable of packaging coins of different width and value constructed in accordance with my invention.

While my device may be constructed to package 50 two types of coins of any different widths and values, such as pennies, nickels, dimes, quarters, half dollars or those of foreign denominations, I

have shown it in the drawings as being adapted to count and package pennies and nickels.

Said device comprises a transparent tube having a side wall 12, at least at the upper end of a greater internal diameter than the diameter of the widest coin to be packaged, to permit a wrapper folded in tubular form to be inserted between said side wall 12 and a stack 14 of coins 16 stacked in said device. Said side wall preferably has its upper end enlarged and curved as at 18 into the shape of a pouring funnel. I preferably provide said side wall with an axial viewing slot 20 extending from the bottom to the top thereof flaring outwardly as at 22 at the upper end thereof. In all instances, I provide said side wall with a transverse slot 24 of a width greater than the widest coin to be packaged which is bisected by said axial slot 20 when employed, said transverse slot 24 being located at a predetermined spaced distance from the lower end of said device. I also provide said member with a preferably flat lower end 26 comprising an annular wall 28 extending inwardly from said side wall 12 to a center hole 30 of a size to admit a finger, having an annular rim 32 projecting upwardly therefrom, having an internal diameter of a size providing a central recess 34 to contain a coin of less width therein. In the present instance, a penny 16 with a stack 14 of a predetermined number thereof to provide a standard package of fifty extending upwardly from the base of said recess 34 to the lower edge 38 of said transverse slot 24.

Said rim 32 has an upper surface 36 of sufficient width so that a coin of a greater width such as a nickel may rest on said upper surface 36 of said rim 32 with a stack of a different predetermined number of nickels thereof sufficient to provide a package of forty nickels extending upwardly to the lower edge of said transverse slot 24. Figs. 3 to 7 illustrate how a stack of coins may be counted and packaged by the use of my invention. As shown in Fig. 3, coins of the said single denomination may be readily dropped within the tubular counter 10. If they are of the size to be contained within the recess 34, the lower edge sinks within the recess aided by a finger inserted through said hole 30, if necessary, and the stack is piled thereon up to the lower edge 38 of said slot 24. The coins need not be counted as inserted, for, as shown in Fig. 3, if an excess number of coins are inserted therein above the lower edge 38 of said slot 24, they may be readily removed therefrom as shown in Fig. 4 by tipping the device so that the excess coins 40 slide out of said slot 24 to insure that the exact number of coins only desired to be packaged is included in said stack 14. In order to insure that the first penny may be inserted within the recess 34, I provide the center finger hole 30 so that the finger may be inserted therein to guide the coin within the recess 34. The correct stacking of the coins may be observed through the transparent side wall 12 and more particularly through the axial slot 20. Then, when the exact number of coins have been piled in the stack 14, a folded tubular wrapper 42, which may be constructed of paper or any suitable material of the size normally used to package the denomination of coins stacked, may have its lower end 44 inserted within the upper end of said container in the space 46 between the inner surface of the side wall 12 of the counter and the periphery of the stacked coins 16 at least a substantial amount below said slot 24 as shown in Fig. 5, the upper end of said tubu-

lar wrapper 42 preferably having its edge turned as at 48 as shown in Fig. 6. The device is then inverted as shown in Fig. 6 so that the stack 14 will slide within the inverted wrapper 42 until the edge of the lowermost penny abuts the turned edge 48 of the wrapper. The wrapper 42 containing the stacked coins may then be removed from my improved counter device 10 and have the edge of its upper end turned as at 50 as shown in Fig. 7, thereby providing a packaged wrapper containing the desired number of coins.

If it be desired to package nickels, nickels are inserted so that the lowermost nickel will have its lower surface adjacent its periphery rest on the upper surface 36 of the rim 32. The distance between the base of the recess 34 and the lower edge 38 of the slot 24 is just sufficient to accommodate fifty pennies, and the distance between the upper edge 36 of the rim 32 and the lower edge 38 of the slot 24 is just sufficient to accommodate forty nickels, and so the nickels may be packaged in exactly similar fashion to the pennies.

It is apparent, therefore, that I have provided a novel type of device for counting coins of different widths and values and packaging them, with the advantages described above.

It is understood that my invention is not limited to the specific embodiment shown, and that various deviations may be made therefrom without departing from the spirit and scope of the appended claims.

What I claim is:

1. A coin packaging device, capable of packaging coins of different width and value, comprising a transparent tube, having a side wall at least at the upper end thereof of a greater internal diameter than the diameter of the widest coin to be packaged to permit a wrapper folded in tubular form to be inserted between said wall and a stack of coins in said device and having its upper end shaped as a pouring funnel and having an axial slot therein flaring outwardly at the upper end thereof, a transverse slot of a width greater than that of the widest coin to be packaged bisected by said axial slot at a predetermined spaced distance from the lower end of said device and a lower end comprising an annular wall extending inwardly from said side wall to a center hole of a size to admit a finger and having an annular rim projecting upwardly therefrom at a distance from said hole, providing a central recess of a size to contain a coin of less width therein to form a stack of a predetermined number thereof extending upwardly to said slot and a coin of greater width to rest on said rim to form a stack of a different predetermined number thereof extending upwardly to said slot, whereby on inversion of said device said stacked coins may slide within a folded tubular wrapper inserted within the upper end of said device.

2. A coin packaging device capable of packaging coins of different width and value, comprising a tube, having a side wall at least at the upper end thereof of a greater internal diameter than the diameter of the widest coin to be packaged to permit a paper wrapper folded in tubular form to be inserted between said wall and a stack of coins in said device and having a transverse slot of a width greater than that of the widest coin to be packaged at a predetermined spaced distance from the lower end of said device and a flat lower end comprising a wall extending inwardly from said side wall to a center hole

of a size to admit a finger and having an annular rim projecting upwardly therefrom at a distance from said hole providing a central recess of a size to contain a coin of less width therein to form a stack of a predetermined number thereof extending upwardly to said slot and a coin of greater width to rest on said rim to form a stack of a different predetermined number thereof extending upwardly to said slot, whereby on inversion of said device said stacked coins may slide within said folded tubular wrapper inserted within the upper end of the device.

3. A coin packaging device capable of packaging coins of different width and value, comprising a tube, having a side wall of a greater internal diameter than the diameter of the widest

coin to be packaged and having a transverse slot of a width greater than that of the widest coin to be packaged at a predetermined spaced distance from the lower end of said device and

5 a flat lower end comprising a wall extending inwardly from said side wall to a center hole of a size to admit a finger and having an annular rim projecting upwardly therefrom at a distance from said hole providing a central recess of a size to contain a coin of less width therein to form a stack of a predetermined number thereof extending upwardly to said slot and a coin of greater width to rest on said rim to form a stack of a different predetermined number thereof extending upwardly to said slot.
